INVENTOR

F. Kroebel

United States Patent Office.

F. KROEGER, OF NEW YORK, N. Y.

Design No. 3,779, dated December 7, 1869.

DESIGN FOR A CLOCK-CASE FRONT.

The Schedule referred to in these Letters Patent and making part of the same.

To all whom it may concern:

Be it known that I, F. KROEGER, of New York city, in the county and State of New York, have invented a new and original Design for Clocks; and I do hereby declare that the following is a full, clear, and exact description thereof, which will enable others skilled in the art to make and use the same, reference being had to the accompanying drawings, forming part of this specification.

The drawing represents a new design for a clock.

This invention relates to a new form of clock-case, and arrangement of dial-plate therein, and consists in the use of an oval frame, A, which contains, near the

middle, the circular dial B, so that above and below the dial, more space is left on the face of the frame than on the sides. The dial need not be exactly in the centre of the frame, but may be shifted slightly upward or downward, or to the right or left of the same.

I claim, as my invention, the design for clocks, as shown.

F. KROEGER.
